UNITED STATES PATENT OFFICE

2,275,900

WELDED BALL PANEL FASTENER

Ralph W. Hall, Cincinnati, Ohio, assignor to The Randall Company, Cincinnati, Ohio, a corporation of Ohio

Application May 31, 1940, Serial No. 338,188

12 Claims. (Cl. 45—138)

This invention relates to fastening devices, and more particularly to fastening devices of the class adapted to securely, though detachably, mount one panel in a flatwise, coplanar manner to a second panel, or other support surface.

Heretofore, it has been common practice, particularly in the automotive industry, to attach upholstery and other finish panels to various body or support panels by means of so-called nail-on strips. Such strips, broadly speaking, consisted of a plurality of spaced nails, the heads of which were welded to a metallic runner, as disclosed by way of example, in the United States Patent No. 2,103,177 issued to H. D. Randall. While nail-on strips have been widely used, they present certain inherent tacking, shipping and safety problems which are lessened or entirely obviated by the fastening device comprising the present invention.

An object of the present invention is to provide attachment means for automotive finish panels, and the like, which will permit rapid and permanent assembly-line attachment of the finish panels to their support panels.

Another object of the present invention is to provide a fastening device for finish panels, and the like, which will permit such panels to be quickly and securely, though detachably, mounted to a support panel without requiring the use of tools, and without the use of auxiliary means such as nails, screws, adhesives and the like.

Another object of the present invention is to provide a mounting strip for finish panels, and the like, with a plurality of substantially spherical attachment members each of which project from and are permanently and rigidly secured to the mounting strip of which they comprise an integral part.

A further object of the present invention is to provide a mounting strip for finish panels and the like, which strip includes projecting attachment members which are characterized by the absence of sharp points, edges or corners upon which persons handling the strips and/or the finish panels to which they are applied, could be injured. This is in keen contrast with the hereinabove mentioned nail-on mounting strips, the nail points of which comprise and constitute a constant source of minor, but nevertheless painful injuries to the workmen.

Still a further object of the present invention is to provide attachment means for finish-panel mounting strips and the like, wherein said attachment means comprise spherical elements of such nature as to permit a plurality of finish pan-

els to be stacked, directly one upon another for shipment or storage. Heretofore, when the finish panels were provided with nail-on mounting strips, it was necessary to physically separate adjacent finish panels to preclude marring, scratching and/or other defacement of the adjacent panels. It was likewise necessary to provide means for preventing bending and other physical damage to the nails themselves during 10 shipment and storage.

Another object of the invention is to provide anchorage or attachment means of the hereinabove stated character which may be inexpensively manufactured and quickly and permanently affixed to the mounting strip by means of spot welding.

A further object of the invention is to provide a plurality of socket members in the support panels to which the finish panels are attached, 20 wherein the socket members are stamped or punched out of the body of the support panel in a single operation, thereby facilitating mass production.

Still a further object of the invention is to provide in a support panel a plurality of socket members which are engageable, one each, by a corresponding attachment member carried by a finish panel and wherein the attachment-member-engaging elements of each socket may be 25 simply and easily reconditioned when their locking characteristics have become impaired after repeated attachment and removal of the finish panel.

These and other objects are attained by the 30 means described herein and disclosed in the accompanying drawing, in which:

Fig. 1 is a perspective view of the upper left corner of a finish panel and a support panel upon which the finish panel is to be mounted, showing 35 the cooperative fastening means of the finish and support panels respectively, which comprise the present invention.

Fig. 2 is a rear view of the upper left portion of the support panel of Fig. 1 with the finish 40 panel secured thereto, showing the inter-relationship between the fastening means of the panels.

Fig. 3 is a vertical section taken on line 3—3 of Fig. 2.

50 Figs. 4, 5 and 6 are sectional views taken on a vertical plane through Y—Y of Fig. 1 showing in sequence a finish panel attachment member abutting, entering and engaging its corresponding socket member of a support panel.

55 Figs. 7 and 8 are modified forms of support

panel sockets comprising a detail of the present invention.

Fig. 9 is an end view of a plurality of fully completed and upholstered finish panels provided with mounting strips of the present invention, stacked one upon another for storage or shipment.

With reference to the drawing, it is noted that broadly speaking, the fastener means of the present invention comprises a spherical ball or anchorage head 10 which is adapted to be engaged by a socket member 11. As illustrated in Fig. 1, anchorage heads 10 project from the rear face of finish panel 12, whereas sockets 11 are provided in the body portion of support panel 13.

For the purpose of illustration, and solely by way of example, the anchorage heads 10 are shown secured to the rear leg 14 of a U-shaped mounting strip 15, which is adapted to be disposed over and engage the outer edge or perimeter of a panel board 16, Fig. 3. A suitable sheet of upholstery material 17 may be secured over the outer face of the panel board by reason of edges 20 thereof being turned over and anchored to the rear face of leg 14 of the mounting strip in any approved manner. A layer of wadding, denoted generally by the numeral 18, may be interposed between the adjacent faces of the panel board and sheet of upholstery, as shown. As illustrated in Fig. 1, those portions of the upholstery edges 20 which engage the rear leg 14 of a mounting strip are cut away, as at 19, adjacent anchorage head members 10. This composite structure comprises the finish panel 12, as shown in Fig. 1.

In the preferred embodiment of the invention, the anchorage heads 10 comprise solid metallic balls, such as bearings, or the like, each of which are permanently secured to the mounting strip by means of spot welding, as indicated at 21. In this manner the entire body portion of each attachment head 10 projects outwardly from the rear face of leg 14, and the front face of the leg at weld 21 is perfectly flat and smooth.

It should be noted that the mounting strips 15 including anchorage heads 10, will in most instances be fabricated at one factory located remote from a second factory where the composite finish panels 12 are fabricated. The completed finish panels are then sent to a third or so-called assembly factory where they are mounted to their support panels. By reason of the inherent characteristics of the attachment heads 10, mounting strips 15 may be shipped to the finish-panel-fabrication-plant without requiring special packaging. It should be further observed that after the mounting strips have been incorporated into a completed finish panel, the anchorage heads project from the rear face thereof in such a manner as to permit a pair of panels C and D to be stacked with the respective attachment heads of one panel abutting the rear face of the other panel as shown in Fig. 9. In this manner a plurality of pairs of finish panels may be stacked, one upon another, for purposes of shipment or storage without damage to the anchorage heads or to the finish panels themselves. It should be further noted, that when thus stacked, the lateral distance between the panels C and D comprising each pair, is equal to the diameter of an attachment head member 10. This distance, it has been found, is approximately one-half of the lateral distance between adjacent finish panels provided with the

so-called nail-on strips, which necessitate the use of inserts to preclude damaging the upholstery fabric by the nail points.

The sockets 11, with which the attachment heads 10 engage, may be punched, stamped or otherwise formed from the body portion of support panel 13, whereby to provide a pair of opposed anchorage lip, wing or tongue elements 30 and 31. With particular reference to Fig. 2, it will be noted that each wing element comprises opposed side edges 32 and a free outer or forward lock edge 33. The rear portion of each wing is integral with the support panel 13. The rear portion of one of the wing elements, such as, by way of example wing element 31, is disposed adjacent a reinforced edge or other reinforced portion of the support panel. Such reinforcing may comprise an out-turned flange 34 formed by cold working the metal, or one or more reinforcing ribs such as 15, Fig. 7. In this manner wing elements 31 are stiffened and rendered more resistant to movement out of the mean plane of the support panel than are wing elements 30. However, it should be observed that neither of the two wing elements 30 and 31 of a socket are resilient in the sense that they will return to the mean plane of the support panel upon being moved out of said plane. Instead, the wing elements are merely yieldable in the sense that they are capable of being moved or bent out of the plane of the support panel by a force applied thereto as when an attachment head is forced therein, as hereinafter more fully described.

The adjacent lock edges 33 of the wing elements of each socket are transversely spaced apart to provide a central socket opening denoted generally by the numeral 35. The opposed side edges 32 of each wing element are preferably spaced from the adjacent edges 36 of the support panel to permit relative movement between the wing elements and the support panel without frictional resistance between edges 32 and 36.

With particular reference to Fig. 2, the lateral distance between adjacent edges 36 of the socket 11 is substantially greater than the diameter of attachment head 10, whereas the transverse distance between the adjacent lock edges 33 is somewhat less than the diameter of an attachment head.

As shown in Fig. 1, the longitudinal axis of each socket is preferably disposed parallel to the edge of the support panel. The term longitudinal axis as used herein extends between and at right angles to edges 36 of a socket.

Each anchorage head may be considered as comprising a forward face 40 and a rear or lock face 41. With reference to Fig. 4, it is seen that the forward and lock faces are disposed on opposite sides of a plane X—X disposed diametrically through head 10 and parallel to the rear leg 14 of the finish strip. It should likewise be observed that each of the forward and rear faces of the anchorage head uniformly and progressively diminish in cross sectional area on opposite sides of plane X—X.

With reference to Figs. 4 to 6 inclusive, it will be observed that as attachment head 10 is moved to the right to engage the opposed lock edges of wing elements 30 and 31, wing 31, hereinafter referred to as fixed wing 31, remains in the plane of the support panel whereas wing 30, herein-after referred to as yieldable wing 30, is forced outwardly and away from the fixed wing 31.

This results in the attachment head 10 being held tightly against the lock edge of the fixed wing in such a manner that as soon as the widest part of head 10 has been forced beyond the free edge of the fixed wing, it will be shifted upwardly wherein the rear face 41 of the attachment head 10 will be engaged, as shown in Fig. 6. Experiment has demonstrated that even though the lock edge 33 of yieldable wing 30 is disposed on the forward face 40, of head 10, that is, to the right of plane X-X, the mounting strip and its associated finish panel are so tightly held against the support panel as to make accidental or unintentional displacement or removal thereof, impossible.

To dislodge the applied finish panel, it is necessary to insert a suitable tool between the adjacent faces of the finish and support panels in order to pry the anchorage heads loose from and out of their respective sockets. During the removal operation, fixed wing 31 may be slightly bent outward, that is, toward the finish panel, thereby permitting head 10 to be drawn out of engagement from yieldable wing 30.

In those instances where the attachment head 25 engaging qualities of the wing elements 30 and 31 become impaired by reason of distortion due to the removal operation, said wings may be reconditioned and returned to the plane of the support panel. The yieldable wings 30 may be bent outwardly, to the left, by means of a screw driver blade or other tool, inserted through central opening 35, and the fixed wings 31 may be bent inwardly, to the right, by means of a light hammer blow. In this manner it is possible and practical to recondition the wing elements so that a finish panel will always snugly abut its support panel regardless of the number of times it is removed therefrom.

The sockets disclosed in Figs. 7 and 8 differ primarily from the sockets disclosed in Figs. 1 and 2 in that the lock edges 50 and 51 respectively, of the opposed wing elements are arcuate and V-shaped in form rather than straight. Such constructions reduce the degree or amount by which the yieldable wing elements 30 need be flexed in order to accommodate passage of the widest portion of an attachment head therebetween.

It should be observed that a finish panel may be applied directly to a support panel without being first shifted relative thereto for the purpose of perfecting engagement of the anchorage heads 10 of the finish panel with the sockets 11 of the support panel. This feature is of particular importance in those instances where control shafts such as door-latch and window-mechanism-control shafts extend outwardly from the support panel and project through the finish panel, as is the common practice in automobile body constructions.

It should likewise be observed that side shifting of an applied finish panel relative to its support panel is effectively precluded by disposing the various socket members at right angles relative to one another. As illustrated in Fig. 1, an anchorage head or ball is free to move or be shifted vertically along its longitudinal axis within and relative to socket A, but is prevented from horizontal movement therein by reason of contact with lock edges 33 of the wing elements 30 and 31. In the same manner, horizontal shifting is possible in socket B, but no vertical shifting is possible. Therefore, it is obvious that sockets A and B cooperate with and are mutually de-

pendent upon each other for nonshiftably supporting the finish panel upon the support panel.

It should be understood that while attachment heads 10 are shown attached to mounting strip 14, which in turn is associated with finish panel 12, such attachment heads may be secured directly to the rear face of metallic finish panels or the like. If desired, the hereinabove disclosed fastener device may be used to secure decorative metallic panels to store fronts, metallic tile to walls, and in all those instances where it is essential to have the outer face of the mounted panel absolutely plane and smooth.

It should be observed, Figs. 5 and 6, that the lock edge 33 of yieldable wing 30 engages the forward face 40 of the attachment head in such a manner as to progressively exert an upward force upon head 10 thereby maintaining the upper portion of said head in constant and continual contact with the lock edge of the fixed wing 30. As the finish panel is forced against the support panel the lock edge of the yieldable wing will be shifted along the forward face of head 10 thereby progressively drawing the lock edge of the fixed wing tighter against the lock face of said head until the lock edge of the yieldable wing is disposed on its maximum diameter, through plane X-X.

From the foregoing, it is apparent that I have provided fastening means for securely, though detachably mounting one panel in coplanar abutment upon another panel. Said fastening means are particularly adapted for mass production fabrication, and are structurally strong and resistant to damage and deformation during shipment and storage. It should be further observed that, due to the absence of sharp projecting points and/or corners, the possibility of injury to workmen handling the mounting strips or the finish panels is reduced to an absolute minimum.

What is claimed is:

1. An upholstery assemblage including a body panel including a support face having a series of spaced sockets therein, each socket including a substantially fixed wing and a yieldable wing both struck from the material of the body panel and located in opposed relationship to one another initially within the plane of said body panel, each wing including opposed sides and a free end, the free adjacent ends of the wings of each socket being spaced apart for defining a central opening, a finish panel for application to said support face, a series of spaced anchorage elements secured to and projecting outwardly from said finish panel, each anchorage element comprising a substantially non-deformable spherical ball like member the diameter of which is greater than the distance between adjacent free ends of the wings of a socket, each ball member adapted to be introduced through the central opening of a socket to be releasably engaged by the wings thereof.
2. A panel assembly which comprises a support panel including a series of spaced sockets, each socket comprising a fixed wing and a yieldable wing spaced from and opposed thereto, each of said wings including a lock edge, the lock edge of said wings being spaced apart to define a central opening, a second panel for application to said support panel, a series of spaced anchorage elements secured to and projecting outwardly from the rear face of said second panel, each of said anchorage elements comprising a round ball 75 the diameter of which is greater than the distance

between the adjacent lock edges of the fixed and yieldable wings of a socket, said ball including a forward and a rear face which progressively increase to and decrease from a maximum diameter of the ball, said ball upon being introduced into said central opening adapted to flex said yieldable wing out of the mean plane of the support panel away from said fixed wing as said ball is moved relative to the fixed wing for locating the rear face of said ball in engagement with the lock edge of said fixed wing, the lock edge of said yieldable wing adapted to engage the forward face of the attachment ball for progressively shifting said ball toward and against the lock edge of the fixed wing as the second panel is forced into coplanar contact with the support panel.

3. An upholstery assembly which comprises a body panel including a support face having a series of spaced sockets therein, each socket comprising a pair of opposed wings, one of which is fixed, the other yieldable, a finish panel for application to said support face, a series of spaced spherical attachment heads carried by and projecting outwardly from said finish panel, said anchorage elements adapted to be engaged one each by the opposed wings of a corresponding socket for supporting said finish panel flatwise against said support face, each attachment head including a forward and a lock face, the fixed wing of a socket adapted to engage the lock face of an attachment head whereas the yieldable wing is adapted to engage the forward face of the same attachment head for maintaining snug engagement between said fixed wing and the lock face of the attachment head.

4. As a new article of manufacture a sheet metal finish strip for finish panels and the like, including front and rear faces and having a series of spaced attachment heads carried by and projecting outwardly from said rear face, each attachment head comprising a ball tangentially contacting at a single point the rear face of said strip, and permanently secured to said strip in the stated relationship by means of welding.

5. As a new article of manufacture a metallic mounting strip including front and rear faces and having a series of spaced anchorage elements carried by and permanently secured to the rear face of said strip, each anchorage element comprising a metallic ball welded directly to the rear face of said strip for providing a spherical shaped body portion projecting from its rear face to provide a bearing surface which progressively increases to and decreases from a maximum on opposite sides of a plane taken through the center of said ball parallel to the plane of the strip.

6. As a new article of manufacture a support panel having a series of spaced sockets provided through its body, each of said sockets adapted to releasably engage a spherical element carried by a finish panel adapted to be mounted flatwise against said support panel, each socket comprising a pair of opposed anchorage lips struck from the body of said support panel, one of said lips being fixed and the other being yieldable to movement out of the plane of the support panel, each of said lips including a forward lock edge, the lock edges of the lips of each socket being spaced apart by a dimension less than the diameter of a spherical element, said yieldable socket lip adapted to be flexed outwardly and away from the fixed lip by the introduction of a spherical element therebetween for disposing the widest portion of said spherical element to the rear of the 75

lock edge of said fixed wing, said yieldable lip adapted to yieldingly engage said spherical element forwardly of its widest portion for maintaining the lock edge of said fixed wing in contact with and to the rear of the widest portion of said spherical element.

7. As a new article of manufacture a sheet metal support panel having a series of spaced sockets formed therein, for the reception of spherical attachment heads carried by a finish panel adapted to be mounted flatwise against said support panel, each socket comprising a pair of opposed wings, each wing including opposed side edges and a lock edge, the lock edges of the wings of each socket being spaced apart to provide an attachment head receptive opening, and reinforcing means provided in said support panel for stiffening one of the wings of a socket for increasing its normal resistance to movement out of the mean plane of the support panel.

20 8. As a new article of manufacture a sheet metal support panel having a series of spaced sockets formed therein, for the reception of substantially non-deformable spherical attachment heads carried by and projecting outwardly from a finish panel adapted to be mounted flatwise against said support panel, each socket comprising a pair of opposed attachment head engaging edges both of which are coplanar with the support panel, and one of which is appreciably stiffer and more resistant to movement out of the mean plane of the support panel than the other.

25 9. As a new article of manufacture a sheet metal support panel at least one edge of which terminates in an out turned flange, a series of spaced sockets formed in the panel for the reception of spherical attachment heads carried by a finish panel adapted to be mounted flatwise against said support panel, each socket comprising a fixed wing and a yieldable wing spaced from and opposed thereto, each of said wings including an attachment head engaging lock edge, the lock edge of the fixed wing disposed in close proximity to the support panel flange in order to partake of the increase in stiffness of the metal resulting from out-turning of the flange, whereas the lock edge of the yieldable wing is disposed remote from said flange.

30 10. As a new article of manufacture a sheet metal support panel at least one edge of which terminates in an out turned flange, a series of spaced sockets formed in the panel for the reception of spherical attachment heads carried by a finish panel adapted to be mounted flatwise against said support panel, each socket comprising a fixed wing and a yieldable wing spaced from and opposed thereto, with both wings disposed initially coplanar with the support panel and normal to the flange, each of said wings including an attachment head engaging lock edge, the lock edge of the fixed wing disposed in close proximity to and in substantial parallelism with the support panel flange whereas the lock edge of the yieldable wing is disposed remote from said flange.

35 11. As a new article of manufacture a sheet metal support panel having sockets formed therein for the reception of attachment heads carried by and projecting outwardly from a finish panel adapted to be mounted flatwise against said support panel, each socket including a pair of opposed wings, each having an attachment head engaging edge, the wings and their head engaging edges being coplanar with the support panel and formed from the material of the support panel,

one wing of each socket being appreciably stiffer and more resistant to movement out of the mean plane of the support panel than the other wing.

12. The assembly which comprises a support member having sockets formed therein, a finish panel for application to said support member, substantially non-deformable anchorage elements providing attachment heads carried by and projecting from said finish panel, each socket com-

prising a pair of attachment head engaging elements coplanar with the support member, one of said elements being appreciably stiffer and more resistant to movement out of the mean plane of the support member than the other, each of said anchorage elements adapted to be releasably engaged by a socket for supporting said finish panel flatwise against said support member.

RALPH W. HALL.
